UNITED STATES PATENT OFFICE.

THOMAS R. BRUMFIELD, OF DANVILLE, VIRGINIA, ASSIGNOR OF ONE-THIRD TO EMIL M. GRAFF AND ONE-THIRD TO EDWARD LEE WALTON, BOTH OF DANVILLE, VIRGINIA.

TOBACCO CONTAINER.

Application filed July 18, 1922, Serial No. 575,772. Renewed October 16, 1923.

To all whom it may concern:

Be it known that I, THOMAS R. BRUMFIELD, a citizen of the United States, and resident of Danville, in the county of Pittsylvania and State of Virginia, have invented certain new and useful Improvements in Tobacco Containers, of which the following is a specification.

This invention relates to shipping containers especially adapted for the reception of leaf tobacco.

The shipping containers now in use cannot be collapsed and consequently only about 16 containers can be returned to the shipping point in each car. Therefor, an important object is to provide a tobacco shipping container which may be conveniently collapsed so that a large number of the same may be returned to the shipping point in one car.

A further object is to provide novel means whereby the ends of the containers may be securely and positively held in position for preventing loss of the contents of the container.

Further, the invention forming the subject matter of this application aims to provide a collapsible tobacco container having novel means whereby the side or body of the same may be opened for exposing all of the tobacco for inspection purposes.

A further and deeply important object is to provide a tobacco container having simple means whereby the staves are so connected that the same may be assembled in barrel formation or laid out flat, and more specifically, the invention aims to provide a novel form of link by means of which the staves are hingedly connected.

Further, the invention aims to provide a collapsible container which is of highly simplified construction, durable in use and cheap to manufacture.

Other objects and advantages will be apparent during the course of the following description.

In the accompanying drawings forming a part of this application and in which like numerals are employed to designate like parts throughout the same,

Figure 1 is perspective of the improved barrel assembled.

Figure 2 is a vertical sectional view through the same.

Figure 3 is a detail sectional view through the barrel.

Figure 4 is a fragmentary perspective of a hoop embodied in the invention.

Figure 5 is a perspective of a number of barrel heads or ends packed for return shipment.

Figure 6 is a fragmentary perspective of a number of the barrel bodies collapsed for return shipment.

In the drawing wherein for the purpose of illustration is shown a preferred embodiment of the invention, the numeral 5 designates the barrel body which consists of a plurality of straight staves 6, the edges of which are beveled so that the body may be arranged in cylindrical formation.

The staves are permanently connected by means of upper and lower hoops each of which is composed of a plurality of links generally designated by the numeral 8. Figure 4 illustrates that each link 8 is formed from a single length of wire bent intermediate its ends to provide a central loop 9, a pair of outer loops 10 and a pair of approximately horizontal arms 11. The ends of the arms 11 are coiled about the outer loops 10 as indicated at 14 and in this manner the several links are connected.

Figure 1 plainly illustrates that the intermediate portions of the arms 11 are securely connected to the staves by staples 16 and the center loops 9 are connected to the staves through the medium of staples 17. It is important to note that the staples 16 and 17 not only secure the hoop to the body of the container but also form a reliable means for preventing distortion of the outer loops 10. That is to say, the center loop 9 cannot be mutilated or distorted as the result of circumferential strain and consequently the outer loops 10 cannot be distorted.

In carrying out the invention, the link 8 at the end of each hoop has its ends extended around the outer loops 10 of the other end of the hoop and then secured to the adjacent stave by staples 20.

The end members are designated by the numerals 22 and are snugly fitted within the ends of the container. Figures 1 and 2 illustrate that the end members are held in position by means of a locking device consisting of a cross 25 and a plurality of locking arms 26 pivoted to the cross as indicated at 27,

The outer portions of the arms 26 are formed with teeth 28 which bite into the body of the container and thereby prevent endwise movement of the end members.

- 5 Figure 2 illustrates the position occupied by the locking device before it is securely engaged with the body of the barrel and it will be seen that the cross 25 is provided with a centrally arranged opening 39 to 10 freely receive a fastening bolt 30. The fastening bolt 30 is freely extended through an opening 32 in the end member 22 and as the bolt may partake of a considerable lateral movement it may be readily passed through 15 the opening 29 when applying the locking device. That is to say, the operator will experience no difficulty in positioning the hole 29 for the reception of the fastening device or bolt 30. When the nut 33 on the 20 bolt 30 is tightened the cross 25 will be forced downwardly with the result that the arms 26 will move radially into engagement with the body of the barrel, whereupon the end members or heads 22 will be securely 25 held in position. Figure 2 illustrates that the inner side of the head 22 is provided with a suitable cap 36 which extends over the head of the bolt 30 and thereby holds the bolt 30 in position.
- 30 In operation, the body of the barrel is arranged in cylindrical formation as illustrated in Figure 1 and the ends of the hoops are extended through the outer loops as illustrated in Figure 1.
- 35 The lower end member 22 is locked in position by the associated locking member formed by the cross 25 and the arms 26, and the container is now filled with tobacco. When the desired quantity of tobacco has 40 been placed in the container, the upper end member 22 is placed in position and is securely locked by the head locking device formed by the members 25 and 26. The container may now be shipped to the desired 45 point and when it is desired to inspect the contents the container is laid on its side and the ends of the hoops separated and the body of the container is then split longitudinally.

In other words, the ends of the body are temporarily separated for exposing the entire contents of the barrel. Bunches of tobacco may be picked from various points by the inspectors and when the inspection is complete the barrel may be again assembled as illustrated in Figure 1.

50 When it is desired to return the containers, a large number of the same may be shipped in a very compact form in the manner illustrated in Figures 5 and 6.

55 I claim:—

1. The combination with a cylindrical container consisting of a plurality of staves, of hoops connecting the staves and consisting of a plurality of links each of which is formed from a single length of metal bent 60 intermediate its ends to provide center and outer loops and a pair of side arms, the ends of the arms being coiled about the outer loops of the adjacent links, and fastening devices connecting the intermediate portions 65 of the side arms to the staves and connecting the center loops to the staves, said fastening devices forming a means whereby to prevent distortion of the center and outer loops.

70 2. A tobacco container comprising a cylindrical body, end members received in said body and having centrally arranged openings, fastening members arranged outwardly of said end members and consisting of crosses and radially arranged locking arms, the ends of which are formed with teeth to engage the body, and fastening bolts 75 extending through said openings and engaged with said crosses.

80 3. The construction set forth in claim 2, and caps extending over the heads of said bolts and holding the same in position.

85 4. The construction set forth in claim 2, said body being split longitudinally whereby the entire contents of the body may be 90 exposed without removing the same.

95 5. The construction set forth in claim 4, and hoops detachably holding the body in cylindrical formation.

THOMAS R. BRUMFIELD.
